UNITED STATES PATENT OFFICE.

EDGAR F. COLLINS, OF SCHENECTADY, NEW YORK, ASSIGNOR TO GENERAL ELECTRIC COMPANY, A CORPORATION OF NEW YORK.

HEAT-TREATING FURNACE.

1,414,180.

Specification of Letters Patent. Patented Apr. 25, 1922.

Application filed February 24, 1920. Serial No. 360,647.

To all whom it may concern:

Be it known that I, EDGAR F. COLLINS, a citizen of the United States, residing at Schenectady, county of Schenectady, State 5 of New York, have invented certain new and useful Improvements in Heat-Treating Furnaces, of which the following is a specification.

The present invention comprises a device 10 for conveying materials to be heated through a heating zone while simultaneously agitating the same to secure a uniform heating effect. My invention is of particular utility for the heat treatment of small parts 15 such, for example, as springs, balls or fittings.

One embodiment of my invention is shown in the accompanying drawing in which Fig. 1 is a vertical sectional view of a furnace 20 and conveyer, and Fig. 2 is a sectional view of a suitable operating mechanism for my device.

Referring to Fig. 1, the furnace here illustrated consists of a container comprising a frame 3 of suitable sheet metal enclosing a fire-brick wall 4 which is lined with a layer of heat-resisting material 5. Embedded in the brick-work of the furnace are a series of outwardly projecting supports 6 consisting 30 of suitable refractory material upon which are mounted resistance heaters 7. A furnace of this general type is described in my prior Patent 1,310,060 of July 15, 1919.

Within the heating zone of the furnace 35 are a series of containers 8, 8^a, 8^b, etc., mounted upon supports 9 in two staggered rows, the respective containers of which being so located that material from one container may be discharged into the adjacent 40 container. In the particular embodiment of my invention shown in Fig. 1 the containers are arranged in two sets, the containers of the respective sets being linked together by rods 10, 11.

45 As shown in Fig. 2 the rods 10 and 11 are connected to suitable mechanism such as pistons 12, 13, mounted within cylinders 14, 15, and arranged to be reciprocated by compressed air, steam, or the like. A mechanism for alternately operating the two series 50 of containers will readily suggest itself. For the purpose of illustration, I have diagrammatically shown supply pipes 16, 17, for conveying compressed air or steam, each 55 containing valves 18, 19, having projecting

members 20, 21, operated by a revolving cam 22. The revolution of the cam alternately engages with the valve stems 20, 21, to admit the compressed fluid first to one cylinder and then to the other. The pistons 12, 13 60 may descend by gravity exhausting the air or steam into the atmosphere through ports 23, 24 which are arranged to open when the cam 22 is not in engagement with the stems 20, 21.

The articles to be heated, for example, a charge of steel balls, are introduced into the heating zone through a charging hopper 25 containing a rotating member 26 so that the charge is introduced intermittently. A 70 quantity of charge when introduced into the furnace first falls into the uppermost container 8^a of one of the series. When the connecting rod 10 is moved upwardly, tilting the container 8^a the charge is transferred 75 into the container 8^b, which is just below container 8^a. The containers are then restored to the position shown in the drawing. When the rod 11 is moved upwardly the charge is transferred from the container 8^b to the container 8^c. An additional quantity of charge is now introduced into the container 8^a. When next the rod 10 is moved upwardly the fresh charge from the container 8^a is transferred into the container 8^b 80 and the original charge now in the container 8^c is transferred to the container 8^d. While the materials are thus being transferred from one container to another and moved progressively through the heating zone of 85 the furnace the charge is turned over and stirred, the materials being brought from the center to the exterior, thereby uniformly heating all parts of the charge. The materials are transferred through a chute 27 90 from the lowermost container 8^d into a tank 28 filled with a suitable cooling fluid 29 such as water or oil. If desired, the materials from this cooling tank may be removed by 95 a link belt conveyer 30, or any other suitable mechanism. As the furnace is closed at its upper or charging end by the revolving door 26 and at the lower end by the liquid seal 29, a non-oxidizing or reducing atmosphere 100 may be maintained within the heating zone.

What I claim as new and desire to secure by Letters Patent of the United States, is,—

1. A furnace for heat treating small parts comprising the combination of an enclosure, charge and discharge means substantially 110

- sealing the interior of said enclosure from the atmosphere, electric resistors mounted within said enclosure for heating a charge therein, a plurality of containers therein located in discharge and receiving relation to each other, and means for tilting said containers to transfer a charge from one container to another thereby causing said charge to receive heat uniformly throughout.
2. A furnace comprising a refractory enclosing envelope, heating means therefor, and a conveyer within said envelope comprising a plurality of separate containers and means for tilting said containers to transfer a charge to be heated from one container to another in the heating zone of said furnace.
3. A furnace comprising a heating chamber, a plurality of containers therein arranged in sets and means for simultaneously transferring materials to be heated from one set of containers to another set of containers.
4. An electric furnace comprising a refractory enclosing container, means for electrically developing heat within said container, means for charging materials to be heated into said container, a plurality of sets of containers arranged in staggered re-
- lation to each other and means for operating 30 said sets of containers to progressively transfer materials to be heated through said furnace by transferring from a container in one set to a container in another set.
5. A furnace comprising a refractory enclosing envelope, a charging device therefor, a plurality of containers located within said envelope and arranged to receive material to be heated delivered by said charging device, means for tilting said containers to deliver 40 said material from one container to another, means for discharging said material from said furnace and a liquid seal for said discharging means.
6. A heat treating furnace comprising an 45 enclosure having an inlet and an outlet, a charging device substantially sealing said inlet from the atmosphere, a plurality of containers in said enclosure, means for uniformly heating said containers by radiation, 50 means for transferring a charge from one container to another, and a discharge device sealing said outlet to prevent access of air into the enclosure.

In witness whereof, I have hereunto set 55 my hand this 20th day of February, 1920.

EDGAR F. COLLINS.
